CLAIM

The ornamental design for a display screen portion with icon, as shown and described.

DESCRIPTION

FIG. 1 is a front view of a display screen portion with icon showing our new design;

FIG. 2 is another front view thereof, but showing additional broken lines; and,

FIG. 3 is an enlarged front view thereof, but shown without the broken lines for additional clarity of illustration.

The broken line drawing of the device, and the symbols, and otherwise images shown in broken lines in FIGS. 1 and 2 are for illustrative purposes only and form no part of the claimed design.
